HAIR ROLLER

Nai-Keung Chen, Fairfield, Conn., assignor to Sperry
Rand Corporation, New York, N.Y.

Filed Sept. 20, 1971, Ser. No. 182,303

Term of patent 14 years

Int. Cl. D28—03
U.S. Cl. D86—10 E

FIG. 1 is a side perspective view of a hair roller showing my new design;

FIG. 2 is a top plan view thereof on an enlarged scale, the bottom plan being a mirror image thereof; and

FIG. 3 is a side elevation thereof on an enlarged scale, showing the side opposite that which is shown in FIG. 1.

The hair roller as shown in FIG. 1 includes a plurality of outwardly extending projections formed integrally with the exterior surface of the roller and a plurality of inwardly projecting elongated flutes formed integrally with the interior surface of the roller. It is understood that said flutes and projections are also respectively included in FIGS. 2 and 3 wherein, for the sake of simplicity, said flutes and projections are partially shown by way of dot-dash notation.

I claim:

The ornamental design for a hair roller, substantially as shown and described.
